UNITED STATES PATENT OFFICE.

HENRY J. BOISSEAU, OF NEW ORLEANS, LOUISIANA.

COMBINED CAP AND HANGER.

1,206,660.

Specification of Letters Patent. Patented Nov. 28, 1916.

Application filed April 13, 1915. Serial No. 21,112.

To all whom it may concern:

Be it known that I, HENRY J. BOISSEAU, a citizen of the United States, residing at New Orleans, in the parish of Orleans and 5 State of Louisiana, have invented certain new and useful Improvements in Combined Caps and Hangers; and I do hereby declare the following to be a full, clear, and exact description of the invention, such as will 10 enable others skilled in the art to which it appertains to make and use the same.

My invention relates to improvements in screw or other caps for closing tooth paste tubes or other similar receptacles for toilet 15 use and resides in the provision of a combined cap and hanger which comprises a cap to act as a closure and means carried by the cap to provide for the hanging of the receptacle to which the cap is attached in the 20 desired position.

Another object is to provide a combined cap and hanger in which the cap element thereof is arranged to act as a guide for the hook, nail or support on which the hanger 25 is to be hung; during the operation of hanging the device, so that the device may be quickly and easily hung up.

Another object is to provide a device of the character described which is comparatively flat thus permitting the storing of 30 large numbers thereof in small space.

Another object of my invention is to generally improve and simplify closure caps for tooth paste tubes and receptacles, shaving 35 stick holders and the like so as to render them more practical and useful without materially increasing the cost of manufacture thereof.

The above and additional objects are accomplished by such means as are illustrated 40 in the accompanying drawings, described in the following specification and then more particularly pointed out in the claims.

With reference to the drawings, wherein 45 I have illustrated the preferred embodiment of my invention as it is reduced to practice, and throughout the several views of which, similar reference numerals designate corresponding parts, Figure 1 is a side elevation of my improved hanger and cap showing it attached to a tooth paste tube and hung upon a hook, Fig. 2 is a vertical sectional view of my improved cap, Fig. 3 is 50 a cross sectional view of a modified form of the invention.

Referring to the drawings by characters

of reference 1 designates a flanged cylindrical cap of the ordinary type that is provided with internal screw threads 2 and is of such shape and size as to be freely turned upon 60 well known tooth paste and shaving stick holding receptacles.

Preferably formed integral with the central part of the cap 1 on the outer face thereof and extending outwardly at right angles 65 thereto is a stud or shank 3 which carries at its outer end a preferably circular or cylindrical head 4. Formed in the head 4 at spaced points are circular hook receiving 70 openings 5, and the outer edge of the head 70 is corrugated or roughened, to prevent slipping of the finger in turning the head.

The head 4 is of greater diameter than the cap 1 and extends beyond the cap sufficiently to dispose the openings 5 to one side 75 of the cap, thus the device may be made comparatively flat since sufficient space between the cap and head to receive a hook like element is unnecessary.

In using my invention the cap 1 is screwed 80 in the ordinary manner upon the screw threaded nipple of the receptacle or tube. A hook 6 is secured to a wall or other suitable support 7 and is extended through one of the openings 5 in the head 4 so as to 85 support the tube or receptacle 8 to which the cap is attached. With my improved cap and hanger it will be seen that the receptacle may be kept properly sealed and easily hung up or removed from the hook. 90

To hang the device the side of the cap 1 is placed in engagement with the bill of the hook and pulled downwardly to direct the bill into one of the openings 5. The inner edges of the openings 5 are in alinement 95 with the outer side face of the cap, thus the bill of the hook is quickly guided into one of the openings when the device is in position as described.

Referring to Fig. 3, 16 designates a 100 flanged cylindrical, screw threaded cap, and 17 an annular flange formed on the cap at the upper end thereof and extending outwardly at right angles to the cap. This flange 17 is flush with the upper end of the 105 cap, is of less thickness than the cap and forms a head similar to the one in the preferred form.

Hook receiving circular openings 18 are formed in the flange or head 17, and are located in the same manner as the openings 5, relative to the cap, thus providing for the 110

guiding of the bill of the hook into the openings.

With reference to the foregoing description and accompanying drawings, it will be observed that the several hanging elements of the cap not only serve as hanging means, but act as handles whereby the caps may be readily screwed or unscrewed.

The device may be quickly hung in view of the guiding action provided by the cap.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as claimed.

What is claimed is:—

- 25 1. The combination with a closure cap for receptacles of a shank carried by the cap and extending outwardly from the outer end thereof, and hanging means in spaced relation with the cap carried by the shank.
- 30 2. The combination with a receptacle closure cap of a shank carried by said cap and extending outwardly from the outer face thereof and a laterally projecting hanging element carried by said shank in spaced relation with the cap and projecting outwardly beyond the same, the side of the cap forming a guiding means for the hook for engaging the hanging element.
- 35 3. The combination with a closure cap, of a shank extending outwardly therefrom and

formed integral therewith, and a circular head carried by said shank and being provided with a plurality of hook receiving openings therein, said cap being arranged to guide the bill of a hook into the said opening.

4. A device of the class described including an interiorly threaded closure cap having vertical side walls and provided with a central upwardly projecting shank rigid with the cap and a circular head consisting of a flat disk centrally connected to the outer end of the shank and being of greater diameter than and projecting outwardly beyond the cap in spaced relation with the top of the same and provided with openings having their inner walls arranged in substantially vertical alinement with the side wall of the cap, whereby the side walls of the cap are adapted to guide the bill of a hook into the said openings, said head being provided with a roughened periphery for screwing the cap on and off.

5. A device of the class described including an interiorly threaded closure cap having vertical side walls and a circular head projecting outwardly beyond the vertical side walls of the cap and provided with vertical openings having their inner walls arranged in vertical alinement with the side walls of the cap whereby the side walls of the cap are adapted to guide the bill of a hook into the said openings.

In testimony whereof I affix my signature in presence of two witnesses.

HENRY J. BOISSEAU.
